UNITED STATES PATENT OFFICE.

MORLEY PUNSHON REYNOLDS, OF CLEVELAND, OHIO, ASSIGNOR TO W. S. TYLER COMPANY, OF CLEVELAND, OHIO, A CORPORATION OF OHIO.

BRAKE-SHOE.

1,155,685.

Specification of Letters Patent.

Patented Oct. 5, 1915.

Application filed August 7, 1914. Serial No. 855,620.

To all whom it may concern:

Be it known that I, MORLEY PUNSHON REYNOLDS, citizen of the United States, and a resident of Cleveland, in the county of Cuyahoga and State of Ohio, have invented a new and useful Improvement in Brake-Shoes; and I do hereby declare the following to be a full, clear, and exact description thereof.

10 My invention relates to brake-shoes and has special reference to what are known as cast brake-shoes, in which the body or braking portion of the shoe is formed of cast metal, such as cast iron, and provided with 15 wire backs cast into such body.

The object of my invention is to provide a cheap, simple and efficient form of this class of brake-shoes, in which the lug or fastener for connecting the shoe to the 20 hanger to support the shoe can be applied to the wire back easily and quickly, and will be securely held in place when the material is cast around the same and said back.

To these ends my invention consists, generally stated in the novel arrangement, construction and combination of parts, as hereinafter more specifically set forth and described and particularly pointed out in the 25 claims.

30 To enable others skilled in the art to which my invention appertains to construct and use my improved brake-shoe, I will describe the same more fully referring to the accompanying drawing, in which—

35 Figure 1 is a top plan view of a brake-shoe embodying my invention. Fig. 2 is a side view of the same partly in section. Fig. 3 is a view of a portion of the back for the shoe, showing lug in section. Fig. 4 40 is a cross-section on the line 4—4 of Fig. 1 looking in the direction of the arrow.

Like symbols of reference herein indicate like parts in each of the figures of the drawing.

45 As illustrated in the drawing 1 represents the usual approved form of a brake-shoe which has its body 2 formed of a frictionally material, such as cast iron, a composition of matter specially prepared or any other 50 suitable material, and to which material a back 3 formed of longitudinal and cross-wires or rods 4 and 5, respectively, is connected, as hereinafter described.

The supporting lug or fastener 6 for connecting the brake-shoe 1 to the usual hanger

or brake-head *a* by the key *b*, shown in Fig. 2 in the usual manner is formed of the usual aquile sheet metal and bent to the usual approved form and shape in any suitable manner. This fastener 6 when so formed 60 has a body portion 7 and supporting legs or standards 8, which are tapered outwardly from said body and the ends of the same are bent to substantially a right angle to said standards, as at 9 to form bearing portions 65 on said fastener.

In the formation of my improved brake-shoe 1, the wires or rods 4 and 5 to form the back 3 are cut to the proper size and such cross-wires 5 are preferably secured to one 70 side of the longitudinal wires 4 by electric welding at their intersections, after which the lug or fastener 6 as formed is connected to such back by passing the bearing portions 9 on the same between the two outer wires 4 75 on each side of the shoe and inserting the outer wires 4 on each side within seats or notches 8' in the standards 8 adjacent to said portions, so that such wires will rest upon said portions. When the lug or fastener 80 6 is thus placed on the wires or rods 4 and centrally of the back 3 formed by such wires and the wires or rods 5, it is locked in such position by bending or compressing the outer wires 4 inwardly as at 4'. The 85 back 3 is now ready for being attached or secured to the body 2 of the shoe 1 by placing such back in a mold, so that it lays against one side of the mold by its wires 4 coming in contact with said side, and while 90 being held in place in any suitable manner, the molten metal to form such body is poured into such mold and around the wires 4 and 5 and bearing portions 9 which not only forms such body but will envelop the 95 wires 5 and such portions and will thus firmly anchor such back on to the moving face or body of such shoe.

It will thus be seen that my improved brake-shoe will have its lug or fastener so 100 connected to the same that it will be securely, firmly and positively held in place, more particularly in the use of such lugs in connection with backs formed of wires or rods for such shoes, while such fastener can 105 be applied to such back and secured in place easily and quickly and will not be liable to pull out or become loosened after it is cast into the body of the shoe with such back.

It will also be seen that by reason of the 110

cross-wires being on the inner side of the back, the back face of such shoe will present a more finished appearance than where the ordinary meshed wire cloth is used for 5 such backs, while in casting the shoe the wires as thus arranged will lie flat against the mold and by reason of the wires being secured at their inter-sections through welded joints such wires will be rendered im- 10 movable, will be a reinforcement to the shoe and will render the shoe less liable to break, while in case of breakage, the pieces will be held to the back and thereby prevent the same or parts of the same from falling 15 down on to the tracks and causing wrecks by the derailment of the car.

It will be obvious that different forms of backs, rods or wires can be used, and that the number of the longitudinal wires or rods 20 can be varied, while various other modifications and changes in the design, application and construction of my improved brake-shoe may be resorted to without departing from the spirit of the invention or sacrificing 25 any of its advantages.

What I claim as my invention and desire to secure by Letters Patent is:—

1. A brake shoe including a body member, rods secured to the back thereof, and a sup- 30 porting lug secured to the rods, said rods being formed to provide means for preventing longitudinal movement of the lug.

2. A brake shoe including a body member, rods carried by the back thereof, a sup- 35 porting lug, and legs formed on the lug for engagement with the rods, said rods being formed to provide means for engaging the legs and holding the lug against longitudinal movement.

40 3. A brake-shoe comprising a body having rods on the back of the same, a supporting lug having legs provided with notches for engaging with said rods to connect the same thereto, and bent portions in said rods 45 for locking said lug thereto.

4. A brake-shoe comprising a body having rods on the back on the same, a supporting lug having legs provided with notches for engaging with said rods to connect the 50 same thereto, bearing portions on the ends of said standards for engaging with said rods, and means formed integrally with said rods for engaging said legs for preventing longitudinal movement of the lug.

55 5. A brake-shoe comprising a cast body

having its back provided with rods cast into the same, a supporting lug secured to said rods, means formed integrally with the rods for preventing longitudinal movement of the lug. 60

6. A brake-shoe comprising a cast body having its back provided with rods cast into the same, and a supporting lug having legs provided with notches and means formed on the rods for holding the lug 65 against longitudinal movement, said means being engageable in the notches.

7. A brake-shoe comprising a cast body having its back provided with rods cast into the same, a supporting lug having legs 70 provided with notches for engaging with said rods to connect the same thereto, and bent portions in said rods for locking said fastener thereto.

8. A brake-shoe comprising a cast body 75 having its back provided with rods cast into the same, a supporting lug having legs provided with notches for engaging with said rods to connect the same thereto, bearing portions on the ends of said legs for 80 engaging with said rods, and means for locking said legs on said rods to prevent longitudinal movement of said fastener on said rods.

9. A brake-shoe comprising a cast body 85 having its back provided with longitudinal and cross-wires cast into the same, said cross-wires being on the inside of said longitudinal wires and integrally secured to the same at their intersections. 90

10. A brake-shoe comprising a cast body having its back provided with longitudinal and cross-wires cast into the same, said cross-wires being on the inside of said longitudinal wires and welded to the same at 95 their intersections.

11. A brake-shoe comprising a cast body having its back provided with longitudinal and cross-wires cast into the same, said cross-wires being on the inside of said longitudinal wires and electrically welded to the same at their intersections. 100

In testimony whereof, I the said MORLEY PUNSHON REYNOLDS, have hereunto set my hand.

MORLEY PUNSHON REYNOLDS.
